UNITED STATES PATENT OFFICE.

CHARLES A. WAITZ, OF ROUSEVILLE, PENNSYLVANIA.

PUMP-BARREL.

1,088,491.

Specification of Letters Patent. Patented Feb. 24, 1914.

Application filed April 1, 1913. Serial No. 758,134.

To all whom it may concern:

Be it known that I, CHARLES A. WAITZ, a citizen of the United States, residing at Rouseville, in the county of Venango and State of Pennsylvania, have invented new and useful Improvements in Pump-Barrels, of which the following is a specification.

This invention relates to pump barrels and consists in certain improvements in the construction thereof as will be hereinafter 10 fully described and pointed out in the claims.

The pump barrel forming the subject of this invention is particularly adapted for 15 deep wells. Such barrels have heretofore been made by providing a tubing or casing and securing within this tubing or casing a liner forming the working surface of the pump barrel. Such constructions under 20 some conditions have developed a difficulty in that the sand packs around the liner making the removal of the liner from the outer casing or tubing difficult.

The object of this invention is to obviate 25 this difficulty.

The invention is illustrated in the accompanying drawings as follows:—

Figure 1 shows a central section through 30 a pump barrel. Fig. 2 a section on the line 2—2 in Fig. 1.

1 marks the fitting at the bottom of the pump barrel. It has the screw threads 2 at the bottom in which the strainer 3 is usually secured. This fitting or coupling 1 also 35 has the screw threads 4 in its upper end into which the outer tubing of the pump barrel is screwed. The coupling or fitting 1 also has the screw threads 6 into which the liner 7 is screwed. The fitting also has 40 the tapered opening 8 extending from the bottom of the liner which forms the seat for the standing valve (not shown). The screw threaded coupling 9 is screwed onto the top of the tubing 5 and the tubing extension 10 is screwed into the top of the coupling 9. It will be understood that the 45 tubing 5 and the tubing 10 are of the usual gage or character of tubes used in wells, the tubing 10 extending to the top of the well. The space 11 between the ends of the tubing 5 and extension 10 is utilized for a 50 closure around the liner 7 and over the space 12 between the liner and the tubing 5. The preferred form of closure is as 55 shown which includes a loose ring 13 which is dropped over the liner 7 and rests on the

top of the tubing 5. A packing or gasket 14 is arranged above the ring 13 and in the space 11.

The gasket 14 and ring 13 form a closure 60 against the passage of sand to the space 12 but are pervious to liquid so that the liquid being pumped fills the space 12 and is subjected to the pressure of the column of liquid in the well tubing 10. This is important in that the liner 7 is made of light 65 gage both for economy in material and economy in space. It will be noted also that the light gage liner 7 will require a finer thread than the ordinary thread used 70 on the tubing 5. If, therefore, the space 12 is packed with sand it will be difficult to remove the coupling because the different pitches of the threads 6 and 4 would result in the stripping of the threads 6. My device, therefore, is particularly desirable with 75 the construction having the screw thread fitting at the bottom with a screw connection between the outer tubing and this fitting and a screw connection between the 80 liner and this fitting.

What I claim as new is:—

1. A pump barrel comprising an outer tubing; a liner secured within the outer tubing, the upper end of the liner being 85 above the top of the outer tubing; a coupling on the top of the outer tubing; an outer tubing extension secured in the upper end of the coupling; and a closure against sand arranged around the liner and between 90 the ends of the outer tubing and the tubing extension.

2. A pump barrel comprising an outer tubing; a liner secured within the outer tubing, the upper end of the liner being above 95 the top of the outer tubing; a coupling on the top of the outer tubing; an outer tubing extension secured in the upper end of the coupling; and a closure against sand pervious to liquid arranged around the liner 100 and between the ends of the outer tubing and the tubing extension.

3. A pump barrel comprising an outer tubing; a liner secured within the outer tubing, the upper end of the liner being above 105 the top of the outer tubing; a coupling on the top of the outer tubing; an outer tubing extension secured in the upper end of the coupling; and a removable ring arranged around the liner and between the ends of the 110 outer tubing and tubing extension, said ring resting on the top of the outer tubing.

4. A pump barrel comprising an outer tubing; a liner secured within the outer tubing, the upper end of the liner being above the top of the outer tubing; a coupling on the top of the outer tubing; an outer tubing extension secured in the upper end of the coupling; and a closure comprising a gasket forming a closure against sand and pervious to liquid arranged around the liner and between the ends of the outer tubing and the tubing extension.
5. A pump barrel comprising an outer tubing; a liner secured within the outer tubing, the upper end of the liner being above the top of the outer tubing; a coupling on the top of the outer tubing; an outer tubing extension secured in the upper end of the coupling; a removable ring arranged around the liner and between the ends of the outer tubing and the tubing extension; and a pervious gasket resting on the ring and extending around the liner and arranged between the ends of the tubing and the tubing extension.
6. A pump barrel comprising an outer tubing; a liner arranged within the outer tubing forming a space between the liner and the tubing; a fitting having a screw thread into which the tubing is screwed; a screw thread of lesser pitch into which the liner is screwed; and a closure around the upper end of the liner closing the space between the liner and the tubing.
- In testimony whereof I have hereunto set my hand in the presence of two subscribing witnesses.
- CHARLES A. WAITZ.
